US0D1022868S

(12) **United States Design Patent** (10) Patent No.: **US D1,022,868 S**
(45) Date of Patent: ** Apr. 16, 2024

(54) **TIRE SIDEWALL**

(71) Applicant: **Bridgestone Americas Tire Operations, LLC**, Nashville, TN (US)

(72) Inventor: **Kevin E. Scheifele**, Atwater, OH (US)

(73) Assignee: **Bridgestone Americas Tire Operations, LLC**, Nashville, TN (US)

(**) Term: **15 Years**

(21) Appl. No.: **29/868,330**

(22) Filed: **Nov. 30, 2022**

(51) LOC (14) Cl. **12-15**
(52) U.S. Cl. **USPC** **D12/605**

(58) **Field of Classification Search**

USPC D12/604, 605
CPC B60C 13/00; B60C 1/00

(57) **CLAIM**

The ornamental design for a tire sidewall, as shown and described.

DESCRIPTION

FIG. 1 is a side elevational view of a first, second, and third embodiment of my new tire sidewall design;

FIG. 2 is a cross-sectional view along cross-section line 2-2 of FIG. 1 of a first embodiment of my new tire design;

FIG. 3 is cross-sectional view along cross-section line 3-3 of

FIG. 1 a second embodiment of my new tire design; and,

FIG. 4 is cross-sectional view along cross-section line 4-4 of

FIG. 1 of a third embodiment of my new tire design.

In the drawings, the broken lines represent environmental subject matter that forms no part of the claimed design.

1 Claim, 2 Drawing Sheets
